UNITED STATES PATENT OFFICE.

MORRISON, M. SHARP, OF WAXAHACHIE, TEXAS, ASSIGNOR OF ONE-HALF TO C. A. SHARP, OF WAXAHACHIE, TEXAS.

SPARK-PLUG PROTECTOR.

1,411,194.

Specification of Letters Patent. Patented Mar. 28, 1922.

Application filed August 16, 1919. Serial No. 317,969.

To all whom it may concern.

Be it known that I, MORRISON M. SHARP, a citizen of the United States, residing at Waxahachie, in the county of Ellis and State of Texas, have invented certain new and useful Improvements in a Spark-Plug Protector, of which the following is a specification.

This invention relates to attachments for spark plugs and more particularly to a protector or shield adapted to be placed over the spark plug to protect the plug from moisture during inclement weather.

One of the primary objects of the invention is to provide a protector hood which may be mounted on the plug and held in position by the usual removable nut so that the hood will be firmly fixed against accidental or casual displacement.

Another object of the invention is to provide a protector hood of this character which will permit a free circulation of air around the plug but which will be arranged as to prevent splashes of water reaching the upper portion or insulator end of the plug.

A further object of this invention is the provision of a device of this character which consists of comparatively few parts, is simple in construction but durable and well adapted to withstand the rough usage to which devices of this character are ordinarily subjected.

For a full description of the invention and the advantages and merits thereof, reference is to be had to the following description and accompanying drawings, in which:

Figure 1 is a side elevation of a spark plug, shown diagrammatically and illustrating the application of the device, the latter being shown in cross section.

Figure 2 is a perspective view of the protector hood in inverted position.

Figure 3 is a perspective view of the complementary shield.

Referring to the drawings, wherein is illustrated the preferred form of my invention, in which like numerals of reference indicate like or corresponding parts throughout the several views, the spark plug A is of any preferred type, the device being adapted to be attached to any of the standard types of spark plugs having the relatively large body portion B and a comparatively small insulator end C. The general

arrangement of spark plugs of this character is such as to provide a shoulder D. The upper electrode of the plug is provided with the usual removable nut E whereby the terminal F of the lead wire may be fixed in position.

The hood 5 consists of the substantially hemi-spherical hollow casing 6, the rounded portion of which is adapted to embrace the insulator C. The rounded portion is provided at its center with a relatively small opening 7 through which the upper electrode is extended as shown to advantage in Fig. 1 thus permitting the terminal F and the removable nut E to be placed in position above the hood. The open end of the hood is provided at its marginal edge with an in-turned flange 8 which is relatively narrow and which thereby forms a circular opening 9 through which the body of the spark plug extends. A complementary shield 10 is provided which consists of a circular disk having a central opening 11 through which the insulator C may be extended. This complementary shield 10 rests upon the shoulder D and its outer diameter is approximately equal to the diameter of the opening 9 in the open end of the hood. The depth of the hood is such as to cause the complementary shield 10 to be disposed within the space embraced by the hood and slightly above the annular flange 8 so that the air is permitted to circulate freely through the interior of the hood but any water splashing up through the opening 9 around the spark plug body will engage the lower surface of the complementary shield 10 and thereby be prevented from splashing up into the hollow interior of the hood. The disk 10 therefore, co-operates with the hood in protecting the interior of the face from the moisture and water which might otherwise gain access thereto.

The fact that the shield is substantially hemispherical will cause it to rapidly drain the water from the top and the flange will prevent the water from passing into the hollow interior of the hood when the water splashes during a severe rainstorm.

The foregoing description and accompanying drawings have reference to what might be considered to be the approved or preferred form of my invention. I desire to be understood that I may make such changes in the construction, combination,

and arrangement of parts, materials, dimensions, et cetera, as may prove expedient and fall within the scope of the appended claims.

5 Having thus fully described my invention what I claim as new and desire to secure by Letters Patent, is:—

10 1. A spark plug provided with an insulator and polygonal body below the insulator, a hood covering the insulator having at its lower end an integral inwardly extending flange opposite the polygonal body, and a baffle supported on the plug and ex-

tending outward above the flange to beyond the polygonal body.

15 2. A spark plug, provided with an insulator and polygonal body below the insulator, a hood covering the insulator and provided with an integral flange extending inward at the top part of and opposite the polygonal body, and a baffle supported on the plug extending outward above the flange to beyond the polygonal body.

20 In testimony whereof I affix my signature.

MORRISON M. SHARP.
